LOOSE LEAF BOOK

Howard Britten Stone, Croydon, England

Application June 24, 1933, Serial No. 677,492
In Great Britain July 6, 1932

9 Claims. (Cl. 129—18)

This invention relates to improvements in loose leaf books of the kind wherein clamping bars for gripping and holding the loose sheets securely between them are drawn forcibly to their sheet holding relative positions by a spring or springs.

According to this invention each clamping bar of hollow construction has sheet aligning posts extending perpendicularly therefrom and mounted so as to be slideable along the bar in the longitudinal direction of the bar. In addition, sheet aligning posts may be provided in fixed positions. The sheet aligning posts are of the usual construction each comprising parts slideable one with in the other.

The slideable sheet aligning posts can be carried on sliders guided within the hollow clamping bars, the slider in each clamping bar having attached thereto one end of a cord which after passing through a hollow sheet aligning post is fixed at its opposite end to a slider in the opposite clamping bar. The sliders are thus connected in pairs. In an alternative arrangement a separate cord is provided for each slider, the opposite end of the cord being, for example, secured to a convenient part of the opposite clamping bar to that in which the slider is movable.

In the accompanying drawing:

Figure 1 is a view of clamping bars in accordance with this invention in their sheet holding relative positions, and

Figure 2 shows a section on the line 2—2, Figure 1.

Figures 3 and 4 are views respectively similar to Figures 1 and 2 showing the positions to which some of the parts are moved when the clamping bars are moved to positions further apart than in Figure 1 in order to release the sheets.

Figure 5 is a diagram illustrating the manner in which sheets or leaves are held between the clamping bars.

Figure 6 is a detail section taken on the line 6—6 of Figure 1, and

Figure 7 is a view similar to Figure 2, illustrating a modified arrangement of the sliders and cords whereby the sliders are moved.

As shown in this drawing, the clamping bars are of hollow construction comprising an inner wall or plate *a* and an outer wall or plate *b* of curved cross section with flanged or channelled edges which can be slid on to the plate *a* longitudinally, for convenience of construction, allowing parts hereinafter described to be assembled with the inner walls or plates and the assembly completed by putting the outer walls or plates *b* in position on the inner walls or plates.

Each plate *a* has hollow or tubular sheet aligning posts *c* rigidly attached thereto, the posts of one plate being slideable within corresponding posts attached to the opposite plate. Springs *d* extending through the tubular posts *c* and concealed therein have their opposite ends anchored by cross bars *e*, the tension of the springs being sufficient to draw the clamping bars together with a force capable of holding the sheets or leaves introduced between the said clamping bars firmly clamped in this position.

In addition to the sheet aligning posts *c* occupying fixed positions on the clamping bars, sheet aligning and locking posts *f* are carried by the sliders *g*, one such slider being provided in each clamping bar. The posts *f* are movable in longitudinal slots *h* in the plates *a*, each of the posts carried by one slider being slideable in or on a corresponding post carried by the other slider.

Springs *i* passing through the posts *f* are anchored to the sliders *g* by cross bars *j* and supplement the springs *d*. Springs *k* are in tension between their attachment to the sliders and their attachment to hooks *l* on the plates *a*, to move the sliders in the same direction, each towards a corresponding end of its path of movement, that is to say, into the position in which the sheet aligning and locking post *f* carried thereby is operative as a sheet locking means. The paths of movement of the sliders are limited by the engagement of the posts *f* with the end walls of the slots *h* which thus serve as abutments for arresting movement of the sliders.

A separate cord *m* is attached to the end of each slider remote from the springs *k* and passed through one pair of posts *c*, blocks *n* with rounded ends being provided to minimize wear at the places where the direction of the cord is changed on emerging from within the said posts. The opposite ends *m'* of said cords *m* are secured by fastenings *m''* to plates *a*. In this way, each cord *m* is secured to a slider in one clamping bar and to the plate *a* of the other clamping bar.

When the clamping bars are close together, that is to say, when they are in the sheet holding positions, the sliders *g* are drawn to one end of their respective paths of movement by the springs *k* and at such times the cord or cords *m*, are slack, as shown in Figures 1 and 2. These cords are preferably made of a relatively inextensible material such as wire. When the clamping bars are moved farther apart, as shown in Figures 3 and 4, the reach of the cord within the posts *c* is lengthened and the reach at the end of a cord attached to a slider is shortened so that

the spring *k* is stretched and the slider moved to a new position, the posts *f* moving in the slots *h*. When the clamping bars are drawn together by the springs *d*, *i* the cords are slackened so that 5 the springs can retract the sliders *g*.

As shown in the drawing, the ends of the cords *m* are threaded through holes in the sliders *g* and are prevented from being drawn entirely out of the holes by knots in the cord or other 10 enlargements. The cords, as shown in Figure 1, are of a convenient length to allow the bars to be moved some distance apart without effecting movement of the sliders against the action of the springs.

15 In the arrangement shown in Figure 7, two sliders *g'* each carrying a post *f* are drawn, one towards the other by a spring *k'*. The sliders *g'* with their posts are drawn apart by cords *m'*, the ends of each cord being attached to sliders 20 in opposite clamping bars by means of the cords being threaded through holes in the lugs *m'* of the sliders and having enlargements at the ends to prevent the cords from being drawn entirely 25 out of the holes. As the posts *f* are moved in opposite directions slots in the sheet to be held thereby corresponding to the slot *q* are appropriately arranged to allow such movement.

Sheets *o* for use with the clamping bars and the aligning and locking posts in accordance 30 with this invention, are provided with straight slots *p* to engage on the posts *c* and angular slots *q* to engage on the posts *f*, as shown in Figure 5. When the clamping bars are drawn apart as 35 in Figures 3 and 4, the posts *f* occupy the positions shown in full lines and the slots *p*, *q* can be placed on the posts *c* and *f* by a sliding movement of the sheet *o*. When the clamping bars move one towards the other to grip the sheets, the 40 posts *f* are moved by the springs *k* to the positions shown in broken lines, the said posts *f* moving into the parts of the angular slots parallel to the edge of the sheets and the edges of the slots abutting against the posts *f* thus afford a further means for retaining the sheets between 45 the clamping bars.

The clamping bars may be moved apart against the action of the springs *d*, *i* by suitable lever mechanism comprising jaws for engaging the inner sides of the clamping bars, or the latter 50 may have holes therein to receive pins projecting from a suitable tool or implement for effecting a separation of the clamping bars against the action of the springs to a sufficient distance to release the sheets from the clamping action of the bars or to permit the introduction of new 55 sheets.

I claim:

1. Mechanism for gripping and holding the loose sheets of loose-leaf books, comprising hollow clamping bars, plates, respectively, slidable longitudinally one within each hollow bar, hollow sheet aligning and locking posts carried by the said slidable plates and extending between and movable longitudinally of the clamping bars to lock the loose sheets in their held positions, and springs for moving the clamping bars to and holding them in their sheet holding positions, said springs being concealed within the sheet aligning posts.

70 2. Mechanism for gripping and holding the loose sheets of loose-leaf books, comprising clamping bars, sheet aligning posts extending between and secured directly to the clamping bars, sheet aligning and locking posts extending between and movable longitudinally of the bars,

plates carrying the said sheet aligning and locking posts and mounted in and slidable longitudinally of each clamping bar, springs for urging corresponding ends of corresponding plates in opposite clamping bars in the same direction, and 5 cords connecting the plates in one clamping bar with the plates in the other clamping bar, said cords passing through the sheet aligning posts secured directly to the clamping bars.

3. Mechanism for gripping and holding the loose sheets of loose-leaf books, comprising clamping bars, sheet aligning posts extending between and secured directly to the clamping bars, sheet aligning and locking posts extending between and movable longitudinally of the bars, 15 plates carrying the said aligning and locking posts, one of said plates being mounted in and slidable longitudinally of each clamping bar, springs for urging corresponding ends of the corresponding plates in opposite clamping bars in 20 the same direction, cord attaching fastenings in each clamping bar, and cords each connecting a slidable plate in one clamping bar to a cord attaching fastening within the opposite clamping bar, said cords passing through the 25 sheet aligning posts secured directly to the clamping bars.

4. Mechanism for gripping and holding the loose sheets of loose-leaf books, comprising clamping bars, sheet aligning posts extending between and secured directly to the clamping bars, sheet aligning and locking posts extending between and movable longitudinally of the bars, plates carrying the said aligning and locking posts and mounted in and slidable longitudinally 35 of each clamping bar, springs for urging corresponding ends of corresponding plates in opposite clamping bars in the same direction, cords connecting the slidable plates in one clamping bar with the plates in the other clamping bar, said 40 cords passing through the sheet aligning posts secured directly to the clamping bars, and wear blocks provided to support the cord or cords at parts where the direction of the same changes.

5. A loose-leaf book comprising clamping bars, 45 sliders movable longitudinally of the clamping bars, sheet aligning posts on said sliders, cord attaching fastenings in each clamping bar and cords respectively secured at one end to a corresponding slider carried by one clamping bar 50 and secured at the other end to the fastening carried in the other clamping bar.

6. A loose-leaf book comprising clamping bars, sliders movable longitudinally of the clamping bars, sheet aligning posts on said sliders, cord 55 attaching fastenings in each clamping bar, springs urging the sliders each towards one end of its path of movement, parts on the bars and sliders for limiting the movements of the sliders, and cords respectively secured at one end to a 60 corresponding slider carried by one clamping bar and secured at the other end to the fastening carried in the other clamping bar.

7. A loose-leaf book comprising oppositely arranged clamping bars, sheet aligning posts in 65 pairs one slidable within the other respectively secured to opposite clamping bars, sliders movable longitudinally of the clamping bars, additional sheet aligning posts in pairs one slidable within the other respectively attached to the 70 sliders carried by opposite clamping bars, and springs urging the sliders each towards one end of its path of movement, and parts on the bars and sliders for limiting the movement of the said sliders.

8. A loose-leaf book comprising oppositely arranged clamping bars, sheet aligning posts in pairs one slideable within the other respectively secured to opposite clamping bars, sliders moveable longitudinally of the clamping bars, additional sheet aligning posts in pairs one slideable within the other respectively attached to the sliders carried by opposite clamping bars, springs urging the sliders each towards one end of its path of movement, parts on the bars and sliders for limiting the movement of the said sliders, and cords extending between opposite clamping bars for moving the sliders against the action of the springs.
- 10 10 15 15
- 5 10 15
9. Mechanism for gripping and holding the loose sheets of loose-leaf books, comprising clamping bars, sheet aligning posts extending be-
- tween and secured directly to the clamping bars, sheet aligning and locking posts extending between and movable longitudinally of the clamping bars, plates carrying the said aligning and locking posts and mounted in and slideable longitudinally of said clamping bars respectively, springs for urging the plates in opposite clamping bars in the same direction, cord attaching fastenings in each clamping bar, cords each connecting a slideable plate in one clamping bar to a cord attaching fastening within the opposite clamping bar, said cords passing through the first mentioned sheet aligning posts, and wear blocks provided to support the cord or cords at parts where the direction of the same changes.
